UNITED STATES PATENT OFFICE.

GEORGE PEEPLES, OF PHILADELPHIA, PENNSYLVANIA, ASSIGNOR OF ONE-HALF TO THE THACKARA MANUFACTURING COMPANY, OF SAME PLACE.

INSULATED PIPE-CO尤PLING.

SPECIFICATION forming part of Letters Patent No. 515,716, dated February 27, 1894.

Application filed June 5, 1893. Serial No. 476,579. (No model.)

To all whom it may concern:

Be it known that I, GEORGE PEEPLES, a citizen of the United States, residing at Philadelphia, in the county of Philadelphia and State of Pennsylvania, have invented certain new and useful Improvements in Insulated Pipe-Couplings, of which the following is a specification, reference being had therein to the accompanying drawings.

10 The object of my invention is to provide an improved form of insulated pipe coupling for combined gas and electric fixtures, of a construction which will at all times and under all conditions be perfectly insulated, as more 15 fully described hereinafter.

In the accompanying drawings:—Figure 1, is a sectional elevation, on an enlarged scale, of an insulated pipe coupling constructed in accordance with my invention. Fig. 2, represents a detached perspective view of the various parts of the same, and Fig. 3, is a view of a modification.

The coupling forming the subject of my invention is so constructed as to be capable 25 of withstanding such strains as may be necessary in straightening the fixture after it is hung in position, without danger of causing the leakage of gas, and the parts are so arranged that moisture due to the deposit of 30 gas tar cannot make contact between such insulated parts, while its small diameter permits its being caught at any point without injuring the coupling.

Referring to the drawings, A, represents 35 the upper section of the coupling, having a threaded opening a , for the admission of the supply pipe, and a threaded neck a' , through which is formed a passage for the gas. The lower section B is provided with a threaded 40 opening b , for the admission of the vertical pipe of the fixture, and between the neck a' and the section B is a ring c , of mica, which forms a perfect insulation between the two parts. In order to prevent the upper end of 45 the fixture from pressing against the mica ring c and injuring the same, a shoulder d is formed at the upper end of the threaded opening b and forms a stop against which the upper end of the conducting pipe may press 50 and form a gas tight joint. The lower section B is in cup like form, and in its threaded

inner wall is screwed a ring e , while to the lower threaded periphery of the neck a' , is screwed a ring e , of a diameter somewhat less than the internal diameter of the cup shaped portion of the lower section B.

The various parts are insulated from each other by mica and rubber or other insulating material, so disposed as to perfectly prevent all danger of accidental contact due either to the straining of the joint or the deposit of gas tar. Between the ring e and the neck a' is a rubber ring g , and between the ring f and threaded inner portion d' of the lower section is a rubber ring h . The rings e and f are insulated by a ring i , of mica or other suitable material and a similar ring h' , of mica, is placed between the ring e and upper section A. As a further precaution a ring k , of hard rubber is placed between the upper portion 70 of the lower section and the mica ring h' .

In manufacturing the couplings for the trade, the opening a for the gas supply pipe is made to fit a pipe of standard size, but if necessary the diameter of the opening may be increased, the external diameter of the upper section being made sufficiently large to permit the drilling of an opening for any ordinary sized supply pipe.

In the modification illustrated in Fig. 3 I have shown an arrangement and construction of parts which may be employed, if it be desired to replace the rubber insulation by porcelain or similar material. In this case the section A is recessed for the reception of the porcelain ring k' and the ring h' , of mica is placed below it so that in screwing the parts together there will be less danger of cracking or breaking the porcelain rings as the mica will yield somewhat to the pressure. The other rubber rings may also be replaced by porcelain, if desired, as illustrated in this figure.

Having thus described my invention, what I claim, and desire to secure by Letters Patent, is—

1. The combination in an insulated coupling, of the upper section, a threaded neck thereon, a ring adapted to such threaded neck, the lower section, a threaded ring adapted thereto, and insulating material provided between the meeting faces of the rings, and the

meeting faces of the rings with the sections, substantially as specified.

2. The combination of the section A, having a threaded neck a' , a ring f , adapted thereto, the lower section B, having an internally threaded portion d , a ring e adapted thereto, insulating rings g and h , located between the rings and the adjacent faces of the opposite sections, and insulating rings c , i , and h' located between the rings e and f and the sections A and B, substantially as specified.
3. The combination of the section A, having

a threaded neck a' , a ring f , secured thereto, the lower section B, the ring e secured thereto, and rings of insulating material, c , g , h , h' , i , and k , disposed between the rings e and f , and the sections to which they are secured, substantially as and in the manner set forth.

In testimony whereof I affix my signature in the presence of two witnesses.

GEORGE PEEPLES.
